ABSTRACT OF THE DISCLOSURE

A ceramic die assembly and method for making same for metal forming operations such as drawing and extruding including a ceramic die body, a supporting retainer ring and a lining interposed between the die body and the retainer ring, where the properties of modulus of elasticity, compressive strength and the hardness of the lining are substantially greater than those similar properties of the retainer ring.

BACKGROUND OF THE INVENTION

Dies for extruding or drawing metals are subjected to extreme loading in both temperatures and pressures. At best, dies wear rather rapidly and must be replaced frequently. The die material conventionally may be combinations of tungsten and chromium steels or other alloys, perhaps including cobalt to increase the hardness of the material and create a more wear resistant surface. Ceramic dies have not been extensively used in ferrous extrusions, due in part to the expense incurred through the high rate of replacement of the retaining rings which support the die. Ceramic dies have good wear resistant characteristics, however, are relatively brittle and have low tensile strengths. Thus, it is necessary to keep them under compression or very low tensile stresses throughout their use. Failure to keep the ceramic die material under such proper loading results in die breakage. Moreover, the inside diameter of the retainer ring may be scored or gouged when the broken ceramic body is either removed for periodic replacement or is torn out during the drawing or extruding process.

Ceramic dies are installed in retaining rings by shrink-fitting in order to keep the ceramic body in compression. If the ceramic body chips or breaks, it may be removed from the retainer ring by any of several methods. Less desirable methods, including heating the ring and pressing the die out or cooling the die and then slipping the die out, consume excessive time and energy. The easiest method of passing the die out of the retainer ring is to press it out, however, this conventionally results in the scoring and gouging of the retainer ring due to the high hardness and abrasiveness of the die material. Subsequent use of the retainer ring is precluded until the interior diameter of the ring has been machined down smooth to remove the burrs and scoring so that in a subsequent interference fit, i.e. shrink-fitting, the die material will not be subjected to localized adverse stresses. It will be appreciated by those familiar with the art that repeated grinding and machining operations enlarge the inside diameter of the retainer ring, and eventually will deprive that ring of enough material to provide a sufficient interference fit which will keep the die in proper compression.

SUMMARY OF THE INVENTION

This invention relates to a ceramic die assembly and a method for making a ceramic die assembly for use in forming operations such as the drawing and extruding of metals including a ceramic die body and a supporting retainer means and a lining interposed between the die

2

body and the retaining means and wherein the lining means has properties of modulus of elasticity, compressive strength, and hardness which are substantially higher than comparable properties of the retaining means.

5 It is therefore an object of our invention to provide a ceramic die and method for making same for forming operations wherein damage to the retaining means by breakup and pull-out of the die body is minimized.

10 A further object of our invention is to provide a ceramic die and method for making same for forming operations wherein a worn die body may be pressed out without damaging the retainer means.

15 A still further object of my invention is to provide a ceramic die and method for making same for forming operations wherein oversized retainer rings may be reclaimed by additional lining.

20 These and other objects of my invention will become apparent upon reading the description of the preferred embodiment which follows.

DESCRIPTION OF THE DRAWINGS

The figure is an exploded view of the ceramic die assembly in accordance with the invention.

DESCRIPTION OF THE PREFERRED EMBODIMENT

25 Referring now to the figure, reference numeral 2 indicates a retaining ring of a generally cylindrical shape having an inside diameter 4. Disposed within the diameter 30 4 is liner 6, also cylindrical in shape and fitting closely thereto. A ceramic die body 8 is then fit within the inside diameter 4 of retaining ring 2, having liner 6 disposed between the die 8 and the ring 2.

35 The embodiment described is a ceramic die assembly for extruding stainless steel tubing utilizing a ceramic die body 8 fit in either a steel or cermet retaining ring 2. It is to be noted, however, that the principles embodied herein may be applied equally well in non-ferrous drawing and extruding and may be of other mounting 40 configurations. The material selected as a liner 6 for retainer ring 2 is chosen according to four characteristic requirements: (1) by hardness relative to both the retainer ring and the die to prevent gouging and scoring of the inside diameter 4 of the retaining ring 2 and the 45 lining 6; (2) good adherence to the retainer ring to make sure that the liner will maintain itself within the inside diameter 4 of the retainer ring and thus be suitable for multiple refit of additional die bodies 8; (3) moderately high elastic modulus both so that deformation will not be concentrated in the liner robbing the liner of its support and the liner will resume its initial 50 internal diameter upon the removal of the worn die and prior to the replacement with a serviceable one; (4) moderately high compressive strength to make sure that the material will not fracture under heavy loading of 55 the die and thus score or gouge the inside diameter of the retaining ring. The retainer ring in the example is AISI H-13 Steel with hardness of R_c 50-52 and with an outside diameter of 5.250" and an inside diameter of 2.440". The inside diameter of the ring was badly 60 scored by previous dies and too large for a sufficient interference fit with another die. The inside diameter was grit blasted with G-16 steel grit at 80 to 90 lbs. pressure removing burrs and gouges preparing it for a lining 6. 65 In so doing the inside diameter of the ring was increased to 2.449". A tungsten carbide coating was placed on the inside diameter 4 of the ring 2 in order to build up the inside diameter to a useable size. The tungsten carbide was in powder form of -200 mesh (by Ro-Tap screen analysis) and containing a blend of approximately 7% cobalt. The carbide coating was placed on the 70 inside diameter 4 by means of a plasma spray coating

process utilizing a nitrogen gas at 50 lbs. pressure and flow rate of 100 cubic feet per hour. The secondary plasma gas was hydrogen also at 50 lbs. pressure with a flow rate of 15 cubic feet per hour. The powder control rate was 30 to 50 lbs./hr. and the electrical power consumed was 400 amps. The coating thickness of the tungsten carbide was put on to a depth of 0.007" or a total of 0.014" on the diameter. The tungsten carbide liner 6 was then ground removing 0.0005" in order to obtain the desired inside diameter to the liner, i.e. 2.440". The ring 2 was then interference fit with a ceramic die by heating the ring up to 950° F. and dropping the ceramic ring into the inside diameter and allowing the retainer ring to cool and shrink to the appropriate fit. After the retainer ring and die in the example were returned to service, twelve extrusions were pushed through the die producing 620 ft. of 1" stainless steel pipe. The die was then taken out of service because it had worn to a size which exceeded tolerances. It is to be noted that the die did not go into tension and break out. When the ring was taken out of service the die 8 was pressed out of the ring, coming out in one whole piece. Previous to our invention, when ceramic dies were pushed out of retainer rings wherein they had been interference fit, the die break up, thus scoring and gouging the inside diameter of the ring. In the instant example the inside diameter of the ring was smooth following the press out and found, when measured, to be the same size as before fitting with a die. The liner 6 had not chipped, spalled or worn and required no additional preparation prior to fitting a second die. The press out of the die interference fit with a liner 6 of our invention required a load of 6,000 lbs. Previous to our invention and without the liner, press out loadings were normally 10,000 to 35,000 lbs. 35 additionally encouraging the break up, scoring and gouging of the inside diameter of the ring. The high modulus of elasticity and the high compressive strength of the liner of our invention insures that the ceramic die, when interference fit within the ring, remains in compression 40 thereby suppressing the tendency of the die to break up. The high hardness of the lining prevents gouging and scoring of the inside diameter of the retaining ring when the die is pressed out by the hard ceramic die. Further, the juxtaposition of the relatively equal but 45 high hardness surfaces of the retaining ring and the liner exhibits a relatively low coefficient of sliding friction between those two surfaces, thus reducing the force requirements to remove a worn die from the retainer ring. The combination of lower force and an easier exit allows the expended die to be removed whole, thus further limiting the destruction and wear of the inside diameter of the retainer ring.

Though the liner 6 described above was of a coating of tungsten carbide laid on the inside diameter 4 of the 50 retainer ring 2, this is considered exemplary rather than exclusionary in that the liner could also consist of a sleeve of similar material also interference fit within the ring between the die and the ring. An alternative

embodiment may include lining means that is formed in situ such as by case hardening the surface of the inside diameter of the retainer ring.

We claim:

- 5 1. A method of making a ceramic die assembly suitable for use in forming operations such as drawing or extruding, which comprises the steps of: providing a ceramic die body and means to support said ceramic body in compression; providing said support means with a lining, said lining having a modulus of elasticity, a compressive strength and a hardness substantially greater than the material from which said support means is constructed; and subsequently assembling said ceramic body within said lined support means, said lining being between said ceramic body and said support means.
- 10 2. A method according to claim 1 wherein said lining is provided by coating said support means with a material which forms said lining.
- 15 3. A method according to claim 2 wherein said support means is coated with powdered tungsten carbide.
- 20 4. A method according to claim 2 wherein said lining material is heated to bond same to said support means.
- 25 5. A method according to claim 2 wherein said lining material is plasma spray coated on said support means.
- 30 6. A method according to claim 1 wherein said lined support means and said ceramic body are assembled by shrink fitting said lined support means about said ceramic body.
- 35 7. A method according to claim 1 wherein said support means is a material from the group consisting of steel and cermet.
- 40 8. A method according to claim 7 wherein said lining is tungsten carbide.
